F. C. TEMPLE,
TRUNK COVER HOLDER,
APPLICATION FILED OCT. 17, 1913.

1,096,964.

Patented May 19, 1914.

UNITED STATES PATENT OFFICE.

FRANK C. TEMPLE, OF BRUNSWICK, MAINE.

TRUNK-COVER HOLDER.

1,096,964.

Specification of Letters Patent.

Patented May 19, 1914.

Application filed October 17, 1913. Serial No. 795,732.

To all whom it may concern:

Be it known that I, FRANK C. TEMPLE, a citizen of the United States, residing at Brunswick, in the county of Cumberland and State of Maine, have invented certain new and useful Improvements in Trunk-Cover Holders; and I do hereby declare the following to be a full, clear, and exact description of the invention, such as will enable others skilled in the art to which it app pertains to make and use the same.

This invention relates to trunk cover holders, and one of the principal objects of the same is to provide simple, reliable, and efficient means for holding the cover of a trunk open so that access may be had to its contents.

Another object of the invention is to provide a prop for the cover of the trunk, box, chest or writing desk which will operate automatically to stop the cover or lid and catch against the stop to prevent the cover from closing.

These and other objects may be attained by means of the construction illustrated in the accompanying drawings, in which—

Figure 1 is a view in side elevation and partial section of a trunk or box with the cover supported by means made in accordance with my invention, a portion of the trunk cover being broken away. Fig. 2 is a sectional view taken on the line 2—2 of Fig. 1. Fig. 3 is a detail perspective view of one end of the metal prop guide.

Referring to the drawing the numeral 1 designates a trunk or box and 2 is the cover thereof. Affixed to one end or side of the box cover is a bracket 3 provided with a perforated lug 4 to which is pivoted a metal prop bar 5 upon the pivot pin 6. The opposite end of the prop bar 5 is provided with a laterally extending lug 7.

Secured in a recess in one side or end of the trunk or box is a prop guide comprising a side member 8 provided with a top portion 9, the latter having a longitudinal slot 10 and the latter having an enlarged portion 11 at one end thereof. The guide member is secured to the side or end of the trunk by suitable fastenings 12. At the bottom of the recess 9 a bearing plate 13 is secured said plate having an offset shoulder 14 and an inclined portion 15 disposed immediately under the large portion 11 of the guide slot

10. The shoulder 14 and the inclined portion 15 are fitted into a corresponding recess 16 in the side or end of the trunk or box, as shown more clearly in Fig. 1, and the guide plate is provided with a stop projection 17 which prevents the withdrawal of 60 the prop bar 5 when the cover is thrown open.

The operation of the invention may be briefly described as follows: When the cover is thrown open the lug 7 will ride along the bearing member 13 until the lug engages the under side of the projection 17 and when the cover is disengaged by the hand of the operator the lug 7 will drop against the shoulder 14 and hold the cover open. When it is desired to close the cover the prop 5 is lifted to disengage the lug 7 from the shoulder and to permit it to move along the bearing member 13 until it reaches the left hand end of the recess 9, as shown in Fig. 1, the bar 5 then resting in said recess and the lug 4 being disposed within the enlarged portion 11 of the guide slot 10 to permit the edges of the cover and the end of the trunk or box to lie closely together when closed.

From the foregoing it will be obvious that a cover prop made in accordance with my invention may be used to advantage on boxes, chests and desks, and that the device is simple in construction, can be manufactured at low cost, and is strong, durable and efficient for its purpose.

I claim:

A trunk cover prop comprising a bar pivoted at one end to the cover of the trunk and the opposite end provided with a laterally extending stop lug, a guide plate secured to the upper edge of one end of the trunk and provided with a longitudinal slot through which said opposite end of the prop bar extends, a bearing plate secured to the upper edge of the end of the trunk in a recess under the guide plate, said bearing plate having a stop shoulder for the lug and an inclined portion back of the shoulder, and the guide plate having a projection to prevent the withdrawal of said lug.

In testimony whereof I affix my signature in presence of two witnesses.

FRANK C. TEMPLE.

Witnesses:

WILLIAM E. RICHARDSON,
ARTHUR J. SNOW.
